DRILLING MACHINE

Frank H. Mueller, Decatur, Ill., assignor to Mueller Co., Decatur, Ill., a corporation of Illinois

Application July 22, 1958, Serial No. 750,130

8 Claims. (Cl. 192—93)

This invention relates to machines for drilling or tapping mains and pipes without escape of fluid pressure therefrom, and more particularly pertains to improvements in the drilling machine disclosed in my copending application Serial No. 552,886, filed December 13, 1955, now Patent No. 2,833,167.

The drilling machine disclosed in the aforementioned patent has a rotatable boring bar and feed mechanism for advancing, or retracting, the bar. The feed mechanism can be operated by hand, but the machine also is provided with an automatic drive for the feed mechanism to advance the boring bar, as it rotates, at a rate appropriate for a cutting operation. The automatic drive includes a clutch mechanism which, upon its disengagement, permits hand advance, or retraction, of the boring bar at a rapid rate by the rotation of a crank handle. The machine also includes a preset feed mechanism which is settable to permit the boring bar to advance, under automatic feed, through a predetermined distance, starting from any selected axial position of the boring bar, and then automatically operates to disengage the clutch mechanism in the automatic drive so that advance of the boring bar will automatically cease.

The clutch mechanism in the aforementioned automatic drive is engageable and disengageable by the axial shifting of a countershaft, and the preset feed mechanism includes a cam arrangement operable to automatically shift the shaft to disengage the clutch mechanism. In actual practice, it has been found that under certain vibratory conditions the cam and cam follower of the aforementioned cam arrangement tend to pound against each other and thereby slowly but surely effect shifting of the countershaft, in a direction to disengage the aforementioned clutch mechanism. Consequently, it is an object of this invention to provide an improved arrangement for yieldably maintaining the cam and cam follower out of engagement until the same are positively operated by the preset feed mechanism.

It also has been found in actual practice that when the countershaft is in its clutch-disengaged position, upon occasion the aforescribed camming mechanism will assume a "dead center" position that will "hang up" and prevent axial shifting movement of the countershaft to its clutch-engaged position. Accordingly, it is another object of this invention to provide an improved arrangement wherein means are provided for preventing the cam parts from assuming the aforescribed "dead center" position.

Other objects and advantages of the invention will become apparent from the following description and accompanying drawings in which:

Figure 1 is a fragmentary longitudinal sectional view of a drilling machine embodying this invention.

Figure 2 is an enlarged fragmentary view of a portion of Figure 1, but showing the countershaft in its clutch-disengaged position.

Figure 3 is an enlarged sectional view taken substantially on line 3—3 of Figure 2.

2

Figure 4 is an enlarged fragmentary view of the countershaft shown in Figure 1.

Figure 5 is a sectional view taken on line 5—5 of Figure 4.

Figure 6 is a fragmentary plan view of the countershaft shown in Figure 4.

Figure 7 is a sectional view taken on line 7—7 of Figure 6.

Referring now to Figure 1 of the drawings, there is shown a drilling machine having a barrel 10 provided at one end thereof with a plate-like eccentric circumferential flange 12, which, in conjunction with a bowl-like top cap 14 bolted thereto, constitutes a gear housing 16. At its other end (not shown) the barrel 10 has secured thereto a driving gear housing (not shown) adapted to be detachably secured to one end of a valve (not shown) through which the boring bar 18 of the machine is adapted to extend for main cutting or drilling operations, all as described more in detail in the aforementioned patent.

Journalled in a bushing 20 in the barrel 10 is the corresponding end of a drive tube 22 which projects into the housing 16 and has a pair of gears secured thereon by a key 28. The other end (not shown) of the tube 22 projects into and is driven from within the aforementioned driving gear housing. Received in the drive tube 22 is the hollow boring bar 18, the upper portion of which has a close sliding fit in the drive tube and is splined thereto for rotation thereby an axial movement relative thereto, preferably by a pair of keys (not shown) secured to the bar and slidable in diametrically opposite interior longitudinal grooves or keyways (not shown) extending the length of the drive tube. The upper interior portion of the boring bar 18 is enlarged to provide a shoulder 30 which supports an inwardly overhanging abutment ring 32 against which is seated a coaxial feed nut 34. The nut 34 is fixed against rotation relative to the bar 18 by keys 36, and fixed against axial movement relative to the bar by a retaining ring 38 threaded into the upper end of the boring bar and locked in place by set screws 40 bearing against the upper end of the nut.

A hollow feed screw 42 is engaged within the nut 34 and depends coaxially within the boring bar 18. The upper end of the screw 42 has an enlarged, unthreaded extension 44 which extends through the upper gear housing 16 and projects through and is journalled in a sleeve bearing 46 supported by the top cap 14. The projecting outer end of the screw extension 44 terminates in a squared or otherwise non-circularly formed outer end 48 for detachable engagement within the complementary socket of a crank handle 50, only a portion of which is shown. Within the gear housing 16 the screw extension 44 has a gear 52 keyed thereto. The feed nut 34 and the feed screw 42 constitute the feed mechanism of the machine for advancing the boring bar 18 on relative rotation between the nut and screw.

An axially-shiftable countershaft 54 is journalled in a cap bearing 56 mounted in the flange 12 and in a sleeve bearing 58 mounted in the cap 14, in laterally-spaced parallel relation to the feed screw 42. At one end the countershaft 54 projects out of the housing 16 and has an operating knob 60 pinned thereto. Mounted on the countershaft 54 is a gear 62 that is selectively connectable and disconnectable with the countershaft for rotation therewith or relative thereto by means of a drive-key type of clutch mechanism. This clutch mechanism includes a spring key 64 received with sliding clearance in a longitudinally-extending slot 66 in the countershaft 54. The base or foot portion 68 of the key is secured in the slot by a transverse pin 70, while

the head 72 of the key is urged by its spring shank 74 to project out of the slot 66 for engagement within a longitudinal groove 76 in the interior of the hub of the gear 62. The key 64 is engaged and disengaged with the gear 62 by axial movement of the countershaft 54, which may be shifted manually by the knob 60. Thus, when the countershaft 54 is in the axial position shown in Figure 1, the key 64 projects into the groove 76 in the gear 62 so as to lock the latter to the countershaft for rotation therewith. When the countershaft 54 is shifted to the left, however, an angular face on the key 64 bears against the edge of an aperture in a bushing 80 on the shaft 54 and cams the key head 72 back into the slot 66 and out of engagement with the gear 62 so that the latter can rotate relative to the countershaft.

Also mounted on the countershaft 54, by a key 82, is a gear 84. The gears 24 and 62 are in constant mesh while the gears 52 and 84 are in constant mesh. Consequently, when the clutch mechanism is engaged, the gears 24 and 62, the countershaft 54, and the gears 82 and 52 form a power train that constitutes an automatic drive for the feed mechanism. The ratios of the gears in the automatic drive are such that when the clutch mechanism is engaged, rotation of the drive tube 22 drives the feed screw 42 at a slightly greater rate of rotation than the feed nut 34 to thereby advance the boring bar 18 at an appropriate rate for cutting a main. When the aforescribed clutch mechanism is disengaged, manual rotation of the feed screw 42, by the crank handle 59, when the drive tube 22 and the nut 34 are at rest, rotates the feed screw 42 at a rate fast enough to rather rapidly thread the nut therealong for a fast advance or retraction of the boring bar 18.

The machine also embodies a preset feed mechanism which can be adjusted so that when the machine is in automatic feed and the boring bar 18 advances a predetermined distance from any axial position of such bar, the automatic drive will be disengaged and stop further advance of the boring bar. For this purpose, the preset feed mechanism includes means for shifting the countershaft 54 from its automatic feed to its hand feed position, i.e., from its clutch-engaged to its clutch-disengaged position. This shifting means includes a cam sleeve 86, shown formed in two parts welded together for manufacturing convenience, which is journaled on the countershaft 54. One end of the sleeve 86 is formed with what may be termed a counterbore that forms a shoulder 88 provided with diametrically opposite, V-shaped cam grooves 90 within which ride the opposite ends of a pin or cam follower 92, extending diametrically through the countershaft 54, when the latter is in its automatic feed position.

It will be seen that if the cam sleeve 86 is restrained against rotation and the countershaft 54 continues to rotate, the projecting ends of the cam pin 92 will ride up the inclined side walls or surfaces of the cam grooves 90 and force the countershaft 54 to shift to the left from its automatic feed to its hand feed position. In such latter position of the countershaft 54, the projecting ends of the cam pin 92 clear the shoulder 88 in the cam sleeve 86 so that the countershaft can rotate freely relative to the cam sleeve and enable operation of the manual feed.

The countershaft 54 is yieldably retained in its automatic feed position by a detent 94 slidable in a radial interior blind socket 96 in the cam sleeve 86 and urged inwardly by a spring 98 interposed between the detent and the base of the socket. It will be noted that the sleeve 86 is provided with a radial bore 100 aligned with the socket 96 so that the spring 98 and detent 94 can be passed through the bore 100 and into the socket in assembling the detent elements with the cam sleeve. The detent 94 has a rounded nose engageable within one or

the other of a pair of diametrically opposite circular recesses 102 in the countershaft 54.

When the detent 94 is engaged with one of the recesses 102 in the countershaft 54, not only is the latter yieldably retained in its automatic feed position, but also the projecting ends of the pin 92 are yieldably maintained out of engagement with the sides of the cam grooves 90, as shown in Figure 1. Consequently, when the cam sleeve 86 is rotating with the shaft 54, no camming action between the pin 92 and the sides of the cam grooves 90 can occur because of hammering action therebetween occasioned by vibratory conditions, because of the out-of-engagement relationship between these parts yieldably maintained by the detent 94 and one of its corresponding recesses 102 in the countershaft 54.

The mechanism for arresting rotation of the cam sleeve 86 constitutes a part of the aforementioned preset feed mechanism that is driven by the gear 26 and which is settable by a rotatable and axially shiftable shaft 104 one end of which projects out of the housing 16 and has a knurled operating knob 106 secured thereon. The details of the preset feed mechanism are described in the aforementioned patent and form no part of the present invention. It is sufficient for the purposes here to point out that the preset feed mechanism includes an arm 108 having an aperture therein rotatably receiving a portion of the cam sleeve 86, and which arm is automatically movable by operation of the preset feed mechanism to the left from the position shown in Figure 1. A counterbore at one end of the aperture in the arm 108 is provided with a radial stop lug 110 (Fig. 3) engageable with a radial lug 112 on and adjacent one end of the cam sleeve 86, when the arm 108 is shifted to the left automatically by the preset feed mechanism, to arrest or prevent rotation of the cam sleeve. As previously described, such arrestment will automatically shift the countershaft 54 from automatic to hand feed position.

The circumferential extent of the cam grooves 90 preferably is such that the shoulder 88 on the cam sleeve 86 is in the form of diametrically opposite narrow edges, as shown in Figure 3. Even so, when the countershaft 54 is in its hand feed position, if the projecting ends of the pin 92 in the countershaft are substantially in angular alignment with the shoulder 88, the pin ends will engage with such shoulders and "hang up," when it is attempted to manually shift the countershaft from its hand to automatic feed position. Such "hanging up" will prevent such shifting from taking place. In other words, the countershaft 54 and the cam sleeve 86 may assume a relative angular position that may be termed "dead center" and which will prevent the aforementioned manual shifting. This invention includes means for preventing the occurrence of such a "dead center" relative angular position.

For this purpose, the countershaft 54 is provided with a circumferential groove 114, spaced axially from the detent recesses 102, in a position to be yieldably engaged by the detent 94 when the countershaft is in its hand feed position to yieldably retain the countershaft in such position. On diametrically opposite sides of the countershaft 54, the groove 114 is provided with a pair of bottom flats 116 extending tangentially of the countershaft and having diverging side walls 118. These flats 116 are spaced angularly with respect to the pin 92, as shown best in Figure 3. In actual practice, a diameter passing perpendicular to the flats 116 is spaced angularly about 33 degrees away from a diametric plane through the countershaft which includes the pin 92. Consequently, it will be seen that when the countershaft 54 is in its hand feed position, if the pin 92 and the cam sleeve 86 should assume their "dead center" relative angular position, the detent 94 will engage at an acute angle with one or the other of the flats 116 and exert a camming action effective to cause relative rotation between the

cam sleeve and the countershaft sufficient to move the pin 92 and the cam sleeve 86 out of their "dead center" relative angular position, as shown in Figures 2 and 3. As a result the countershaft 54 can always be shifted by hand.

It thus will be seen that the objects of this invention have been fully and effectively accomplished. It will be realized, however, that the foregoing specific embodiment has been shown and described only for the purpose of illustrating the principles of this invention and is subject to extensive change without departure from such principles. Therefore, this invention includes all modifications encompassed within the spirit and scope of the following claims.

I claim:

1. Shiftable apparatus comprising: a shaft member; a sleeve member on and rotatable with said shaft member, a first of said members being shiftable axially by hand between first and second positions and a second of said members being fixed against axial movement with said first member; means defining a cam surface on one of said members inclined to their axes; a radial cam follower on the other of said members effective in one of said positions of said first member to engage said surface and shift said first member automatically to the other of said positions on relative rotation between said members in at least one direction; and detent means interengaged between said members in said one position of said first member to yieldably restrain shifting of the latter to said other position and also to yieldably restrain said relative rotation and yieldably maintain said follower and said surface out of engagement with each other.

2. The structure defined in claim 1 in which the detent means includes means defining a circular recess in one of the members and a detent element on the other of said members having a rounded nose receivable in said recess.

3. The structure defined in claim 1 in which there are two diametrically disposed cam surfaces, two diametrically disposed cam followers cooperative with said surfaces, and the detent means includes means defining two diametrically disposed circular recesses in one of the members and at least one detent element on the other of said members having a rounded nose receivable in either of said recesses.

4. Mechanism for operating a clutch comprising: a clutch-operating shaft shiftable axially by hand between clutch-engaged and clutch-disengaged positions; a sleeve on and rotatable with said shaft but fixed against axial movement therewith, said sleeve having in an end edge thereof a pair of diametrically-disposed notches, each having side wall camming surfaces that converge longitudinally inwardly of said edge; a pair of diametrically-disposed cam follower projections on said shaft receivable in said notches without engagement with said surfaces in one of said shaft positions, said projections being effective to engage a corresponding pair of said camming surfaces and shift said shaft automatically from its said one position to the other on the arrestment of rotation of said sleeve with said shaft; means defining a pair of diametrically-disposed circular detent recesses in said

shaft; and a spring-pressed radial detent element on said sleeve having a rounded nose yieldably receivable in one of said recesses in said one shaft position to yieldably restrain shifting of said shaft to said other position and also to yieldably maintain said projections out of engagement with said camming surfaces during rotation of said sleeve with said shaft.

5. Shiftable apparatus comprising: a shaft member; a sleeve member on and rotatable with said shaft member, a first of said members being shiftable axially by hand between first and second positions and a second of said members being fixed against axial movement with said first member; means defining a cam surface on one of said members inclined to their axes; a radial cam follower on the other of said members effective in one of said positions of said first member to engage said surface and shift said first member automatically to the other of said positions on relative rotation between said members in at least one direction, said inclined cam surface at one end thereof merging into a surface portion which, if engaged by said follower on initial movement of said first member to shift from said other to said one position, causes said follower to "hang up" and prevent completion of said shifting movement; and separate cam surface and yieldable follower means on said members interengaged in said other position for yieldably urging said members into a relative angular position wherein said radial cam follower is out of longitudinal alignment with said surface portion, whereby said first member can be shifted by hand from said other position to said one position without "hanging up."

6. The structure defined in claim 5 in which the separate cam surface and yieldable follower means includes means defining an elongated transverse surface portion on one of the members substantially non-convex in section taken transversely of said members, and a yieldable radial detent element on the other of said members engageable with said surface portion.

7. The structure defined in claim 6 including means defining a circular detent recess in the one member engageable by the detent element in the one position to yieldably restrain shifting of the first member to the other position and also to yieldably restrain said relative rotation and yieldably maintain the radial follower and the inclined cam surface out of engagement with each other.

8. The structure defined in claim 6 including a circumferential groove in the one member engageable by the detent element in the other position to yieldably restrain shifting of the first member to the one position, and wherein the transverse surface portion defines a portion of said groove.
